UNITED STATES PATENT OFFICE.

HORACE D. LORCH, OF LOUISVILLE, KENTUCKY, ASSIGNOR, BY DIRECT AND MESNE ASSIGNMENTS, OF FIFTY-ONE ONE-HUNDREDTHS TO LORCH CONSTRUCTION CO., OF TULSA, OKLAHOMA, A CORPORATION OF OKLAHOMA, AND FORTY-NINE ONE-HUNDREDTHS TO SAM Z. LORCH, OF LOUISVILLE, KENTUCKY.

APPARATUS FOR REFINING MINERAL OILS.

1,264,668.

Specification of Letters Patent. Patented Apr. 30, 1918.

Application filed September 7, 1916, Serial No. 118,891. Renewed November 24, 1917. Serial No. 203,674.

To all whom it may concern:

Be it known that I, HORACE D. LORCH, a citizen of the United States, residing at Louisville, in the county of Jefferson and State of Kentucky, have invented certain new and useful Improvements in Apparatus for Refining Mineral Oils, of which the following is a specification.

The present invention covers an apparatus for refining crude oil and converting the same into a plurality of purified products or fractions, and has particular reference to means for carrying out of such steps in a simple and expeditious manner, without incurring material losses by the formation of waste products. A further object is to provide apparatus for producing from crude oil an enlarged quantity of gasolene or benzin, to convert a portion of the kerosene into gasolene or benzin, to convert a portion of the heavy fuel oil into gasolene or benzin, to separate, purify, clarify, deodorize and refine the main products of the process, and to produce valuable by-products.

The accompanying drawings show one form of apparatus constructed in accordance with my invention.

In said drawings Figure 1 shows a side elevation of an entire arrangement of apparatus embodying my invention. Fig. 2 shows an improved form of the vapor separating and filtering device. Fig. 3 shows on an enlarged scale a vertical elevation of one of the vacuum liquid separators, in which two or more may be employed, and Fig. 4 shows on a somewhat larger scale connections at the top of the liquid vacuum separator.

In said drawings 1 is an ordinary crude oil still, which may be of any desired or well-known construction and heated in any appropriate manner. From this still leads a vapor pipe 2 into the lower part of the vapor filter and separating device 3. From the top of this device extends an outlet pipe 4, and from a point somewhat below the top extends another outlet pipe 5, which pipes may be connected and lead to the common condenser 6, or if desired the materials flowing through these two pipes 4 and 5 may be led off through separate condensers and such further treating apparatus as may be necessary.

From the lower part of the condenser 6 a pipe 7 carries the distillate to an agitator 8, in which the material is perfectly mixed with a quantity of water or other purifying liquids, after which the mixture flows through pipe 9 into the vacuum separator 10.

From the lower part of the vapor filtering device 3, but above the bottom, an outlet pipe 11 conveys the vapors to a condenser 12, from which the condensate is carried by pipe 13 to an agitator 14 in which the condensate is mixed with water or the like, and the mixture carried through pipe 15 into the vacuum separator 16.

From the bottom of the vapor filter 3 a pipe 17 draws off the heaviest of the vapors, together with any condensed liquid, and may return the same, to a valve 18 and pipe 19 to still 1, or in case it is so desired, may draw off the same through the valve 18 and pipe 20 for other use.

The vapor filter and separating device illustrated in Fig. 2 on a larger scale constitutes an important part of my invention. The vapors entering through the inlet pipe 2 enter the space 22, and in this space solid material, any condensed material and the heavy vapors, which are not in condition for further treatment, settle out and are drawn off as above stated through pipe 17. The lighter vapors flow upwardly through the space surrounding the pan 25, which pan rests upon brackets 23, and is held in proper place by the spacers 24.

In the vapor chamber 26 a further stratification of the vapors takes place, the heaviest of the vapors going to the bottom of this space which is pan 25, and being drawn off by pipe 11, while the lighter of these vapors pass upwardly through the space surrounding pan or basin 29, into the vapor space 30 (which space of course includes the space inside of the pan 29 and the space above the same). The heavier of the vapors in the space 30 are drawn off through the pipe 5, while the lighter of these vapors, and the gases present, are drawn off through the pipe 4. As above stated, the pipes 4 and 5 may be connected to a single condenser, or these pipes may convey the vapors to independent treating means.

Referring now more particularly to Fig. 3, the material, consisting of a mixture of

oil and water, together with some impurities, is drawn in to the vacuum separating device 10, through the pipe 9. The pipe 9 is connected by valve 31 and nipple 33 to the 5 casing of the vacuum separator 10. At the top of the valve 31, and opposite the pipe 9 is a nipple 32, provided with a suitable closure, which may be used for removing any obstructions from the interior of the 10 valve casing. At 34 is shown a gage, which may be of any usual or preferred structure to show the height and character of the liquid in the separator 10. At the bottom of the vacuum separator 10 is an outlet 35, 15 controlled by regulating valve 35^x.

About midway of the height of the vacuum separator 10, but below the inlet 33 is an oil outlet 36, which is connected by the connections 36^x and 37 with a series of pipes 38, 20 leading to different tanks or receptacles, into which the product is run. These pipes are provided with suitable shut-off valves 38^x.

At the upper part of the vacuum separator 10, I provide a steam pressure pipe 39. 25 This is connected through valve pipe 40, valve 41, with an injector, said injector comprising connection 42 and pipe 43, in which is placed an extension of the pipe 40, as shown at 45, at the end of which is placed 30 a jet 47, connected by the union 46. By removing the connection 46, a different sized jet 47 may be substituted, to produce any desired amount of force to the injector apparatus. At 44 is shown a connection between 35 the part 42 and the upper end of the vacuum separator 10.

By referring to Fig. 1 it will be noted that there are two separators, 10 and 16 respectively. These two separators may be 40 built exactly alike, so that Figs. 3 and 4 show the detailed construction of both these devices.

The operation of the apparatus is as follows:

45 Crude petroleum of any suitable kind is placed in still 1, heated in any appropriate manner and the vapors passed by pipe 2 into the vapor filter and separating device 3, in which they are separated into four or more 50 fractions, depending upon the respective weights of such fractions, the heaviest being drawn out through pipe 17, the next heaviest through pipe 11, and the next heaviest through pipe 5, and the lightest through 55 pipe 4. In principle I preferably so regulate the valves that the material drawn out through pipe 11 constitutes that fraction corresponding substantially to the kerosene fraction, and so that the pipes 4 and 5 will 60 carry off the lighter material, suitable for condensing and refining to produce high grade gasoline or benzine.

From the pipe joining 4 and 5, the vapors are led to a suitable condenser that is of any 65 approved type, through pipe 7 into agitator

8. In this agitator the condensate is mixed with a suitable amount of water, any preferred mixing arrangements being provided therein, and the mixture of oil and water passes off through pipe 9, into vacuum separator as above described and as more completely illustrated in Fig. 3. 70

By injecting steam from a pipe 39 through the injector 47, a partial vacuum is produced in the vacuum separator 10, so that the oil 75 and water will quickly separate therein, the oil being drawn off through pipe 36 and the water being drawn off through pipe 35 and valve 35^x. By regulating the valves 31, 35^x, 38^x and 41 just the proper amount of vacuum 80 may at all times be maintained in the vacuum separator 10, to enable the proper functions to be carried out and produced in this separator.

I desire to call attention to the fact that it 85 is not necessary to purify the condensed oils by any chemical process whatever, and thereby a considerable saving in the cost of refining is secured.

While I have described the same treatment 90 as being applied to the two separate fractions, I desire to state that in some cases it might be advisable to differently treat such fractions.

Also by the provision of suitable outlet 95 pipes, any desired number of fractionations can be made.

Furthermore, the apparatus may be employed in treating vapors arising from the 100 boiling in coke stills of tar wastes and fuel oils in the same manner as in treating vapor from crude oil. All the liquids in crude oil, except the wax moreover can be extracted and converted and the residua reduced to a fuel coke of commercial value. 105

Having thus described my invention I desire to state that the invention is not limited to all the precise details as above mentioned, but only by the appended claims, and what I claim is:—

1. In apparatus of the character set forth, 110 the combination with a vapor producing means, of a vapor separating chamber for separating the heavier and lighter fractions while vaporized, means for creating predetermined partial vacua in different portions of the vapor separating chamber and separately drawing off the different fractions from said different portions while still in 115 vaporous condition, and means for condensing the vapors after their withdrawal from the separating means.

2. In apparatus of the character set forth, 120 the combination with a vapor producing means, of a vapor separator having means for separating the heavier and lighter fractions while vaporized, means for creating partial vacua in different portions of the separator for separately drawing off the different fractions from said different portions 125 130

of the separator while still in vaporous condition, means for condensing the vapors after their withdrawal from the separating means, and means for changing the amount of vacuum in the said different portions of the separator.

3. In apparatus of the character set forth, the combination with vapor producing means, of a vapor separator comprising a 10 casing having compartments for respectively receiving heavier and lighter fractions of vapor, means for delivering the vapor from the producing means to the separator, and means for causing the stratification of the 15 different fractions respectively in their different compartments, said means including separate outlet pipes communicating with the different compartments, condensing means connected to the outlet pipes, means 20 for causing a partial vacuum in each of the different outlet pipes and varying the amount of such vacuum to cause the separa-

tion of the vapors, and means for condensing the vapors after their removal from the separator.

4. In apparatus of the character set forth, the combination with a vapor producing means, of a vapor separating chamber, means for delivering vapor from the producing means to the chamber, a plurality of 30 vapor outlet pipes leading from different portions of the chamber, condensers for the outlet pipes disposed outside the separating chamber, and means connected to the pipes beyond the condensers for creating a partial 35 vacuum in each of said pipes and varying the amount of such vacuum.

In testimony whereof, I affix my signature in the presence of two witnesses.

HORACE D. LORCH.
